[57] CLAIM

The ornamental design for a faucet spout, as shown and described.

DESCRIPTION

FIG. 1 is a front perspective view of a faucet spout showing my new design;
FIG. 2 is a rear perspective view thereof;
FIG. 3 is a top plan view thereof;
FIG. 4 is a front elevational view thereof;
FIG. 5 is a right side elevational view thereof, the left side being a mirror image;
FIG. 6 is a rear elevational view thereof; and,
FIG. 7 is a bottom plan view thereof.
The broken line showings of the aerator in FIGS. 1-2, 4-5 and 7, of the handle in FIGS. 1, 4 and 5, of the bonnet nut in FIGS. 1 and 4-5, and of the escutcheon in FIGS. 1-6 are for purposes of illustration only and form no part of the claimed design.
